UNITED STATES PATENT OFFICE.

JOHN F. O'CONNOR, OF CHICAGO, ILLINOIS, ASSIGNEE TO WILLIAM H. MINER, OF CHAZY, NEW YORK.

SNAP-LOCKING YOKE.

1,286,739.

Specification of Letters Patent. Patented Dec. 3, 1918.

Application filed April 27, 1918. Serial No. 231,106.

To all whom it may concern:

Be it known that I, JOHN F. O'CONNOR, a citizen of the United States, residing at Chicago, in the county of Cook and State of Illinois, have invented a certain new and useful Improvement in Snap-Locking Yokes, of which the following is a full, clear, concise, and exact description, reference being had to the accompanying drawings, forming 5 a part of this specification.

This invention relates to improvements in snap locking yokes.

One object of the invention is to provide a hooded yoke for railway draft riggings 15 having integral means coöperable with the shoulders of a standard draw bar and so designed that, when the yoke and draw bar are assembled with the elements of a shock absorbing mechanism, the yoke and draw 20 bar are operatively connected and positively prevented from disengagement.

Another object of the invention is to provide a yoke for railway draft riggings, wherein the yoke is formed with inherently 25 resilient yoke arms adapted to be sprung from normal in such a way as to permit a draw bar butt to be slipped into position with respect to the yoke arms, the yoke arms upon being released then automatically 30 springing into operative position.

In the drawing forming part of this specification, Figure 1 is a side elevational view of a portion of a draw bar and one form of my improved yoke connected thereto. 35 Fig. 2 is a top plan view of the structure illustrated in Fig. 1, parts of the yoke being broken away. Fig. 3 is a vertical, transverse, sectional view, taken on the line 3—3 of Fig. 1. Fig. 4 is a longitudinal, vertical, 40 sectional view, taken substantially centrally of the draw bar and yoke and illustrating the manner in which the yoke arms are adapted to be sprung from normal position to permit the insertion or removal of the 45 draw bar, the latter being shown in elevation. Fig. 5 is a view corresponding to Fig. 1, but illustrating another embodiment of the invention. And Fig. 6 is a transverse, sectional view, taken on the line 6—6 of 50 Fig. 5.

Referring first to the construction illustrated in Figs. 1 to 4, inclusive, 10 denotes the shank of a standard draw bar having the butt thereof provided with the usual upper and lower shoulders 11 and 12. The im-

proved yoke is designated generally by the reference A.

As shown, the yoke A is in the form of a casting or other suitable material having the quality of inherent resiliency to permit flexing of the upper and lower yoke arms 13 and 14. The yoke arms are preferably integrally connected at their rear ends, as indicated at 15.

At their forward ends, the yoke arms 13 and 14 are provided with spaced side plates 16 and 17 respectively, the former extending downwardly from the main portion of the arm 13 and the latter extending upwardly from the main portion of the lower 70 arm 14. It will be evident from inspection of Figs. 1, 3 and 4, that the effect of a hollow rectangular hood is produced at the forward end of the yoke within which the butt of the draw bar is adapted to be received. 75

The yoke arms 13 and 14 are provided with transversely extending gibs or shoulders 18 and 19 respectively, adapted to co-operate with the draw bar shoulders 12 and 11, respectively. It will be noted that the 80 transverse shoulder 19 is formed at the upper portion of the side wall 17 which constitutes a portion of the lower yoke arm 14 and similarly, the shoulder 18 is formed at the lower portion of the wall 16 which is 85 made integral with the upper arm 13.

In order to brace the upper shoulder 19, a substantially triangular shaped integral web 20 is provided and a corresponding similar web 21 is formed integrally with the shoulder 18 at the bottom of the draw bar butt. The forward end of the upper arm 13 is suitably cut away, as indicated at 23, to provide the necessary clearance for the 90 web 20.

As clearly appears from Figs. 1 and 4, the triangular shaped front ends of each of the yoke arms and the triangular webs 20 and 21 are normally spaced from the adjacent upper and lower surfaces of the draw 100 bar butt, a distance equal to or slightly greater than the distance which the shoulders 11 and 19 and 12 and 18 are overlapped so that the arms of the yoke may be sprung or forced toward each other in the manner 10 indicated most clearly in Fig. 4 and thus separate the shoulders 18 and 19 a distance sufficient to permit the insertion and withdrawal of the draw bar butt.

The manner of assembling the draw bar 11

and yoke will be apparent from the preceding description, particularly when considered in connection with Fig. 4. Upon release of the forces utilized to compress or spring together the arms of the yoke, the latter will automatically spring back to their normal parallel position, as indicated in Fig. 1. When the shock absorbing mechanism is inserted within the yoke, the front follower 24 thereof (which is indicated by dotted lines in Fig. 1) will, of course, prevent the arms of the yoke being sprung together. Obviously, the yoke arms can not be spread apart from their normal position due to the engagement of the draw bar with the said webs 20 and 21. In other words, when the draw bar and yoke are assembled and in position, the draw bar and yoke are effectively interlocked and can not be disconnected. In this manner, I obtain a detachable draw bar and yoke connection without the aid of any transverse keys or other detachable members, the locking elements being integrally formed on the yoke and the latter being adapted for coöperation with any standard draw bar whether the latter has coupler key slots or not.

In the form illustrated in Figs. 5 and 6, the draw bar 110 is shown as of the standard type having upper and lower shoulders 111 and 112. The yoke A' has similar parallel arms 113 and 114 as the yoke shown in the first four figures. In this form, however, the upper yoke arm 113 is provided with an integral upper transverse shoulder or gib 118 and the lower yoke arm with a corresponding lower transverse shoulder or gib 119. Said shoulders 118 and 119 are coöperable respectively with the draw bar shoulders 111 and 112.

In order to form the hooded effect for inclosing the draw bar butt, the lower yoke arm 114 is provided with an upwardly extending side wall 117 and the upper yoke arm with a downwardly extending opposed side wall or plate 116.

The construction shown in Figs. 5 and 6 is slipped over the draw bar or the latter slipped within the yoke by spreading the yoke arms 113 and 114 from normal a distance sufficient to let the draw bar butt pass between the shoulders 118 and 119.

In order to prevent disengagement of the draw bar and yoke after the same are assembled, the side wall 117 is provided at its upper end with a rearward extension 40 and the other side wall 116 with a lower rearward extension 41. Said extensions 40 and 41 are of such length as to overlap the usual front follower 124 of the shock absorbing mechanism so that, when the follower is in place, the yoke arms 113 and 114 cannot be spread apart, as will be apparent from inspection of Fig. 5. The extensions 40 and 41 will be made long enough so as to always

insure their engagement with the follower 124 even under the maximum draft.

Although I have herein shown and described the preferred manner of carrying out my invention, the same is merely illustrative and I contemplate all changes and modifications that come within the scope of the claims appended hereto.

I claim:

1. In a yoke of the character described having integrally formed upper and lower arms, each arm having a transverse shoulder adapted to coöperate with a shoulder of a standard draw bar, said yoke being formed of inherently resilient material permitting flexing of the yoke arms from normal position, said yoke having means coöperable with a draw bar and the front follower of a shock absorbing mechanism when the three said elements are assembled, said means preventing said yoke arms from being flexed in either direction from normal position. 75 80 85

2. As an article of manufacture, a yoke for railway draft riggings, said yoke including a pair of upper and lower spaced, integrally formed yoke arms, one arm having a side plate at one side of the yoke and the other arm a side plate at the opposite side to thereby form a hood at the forward end of the yoke, said yoke arms having means coöperable with the shoulders of a standard draw bar butt for operatively connecting the yoke to a draw bar. 90 95

3. The combination with a draw bar having a shouldered butt, of a yoke, said yoke having a hooded forward end within which the butt is received, a horizontal and a side wall being formed integrally with each yoke arm, said yoke arms being adapted to be sprung from their normal parallel position, and means coöperable with the shoulders of the draw bar for operatively connecting the yoke and draw bar. 100 105

4. As an article of manufacture, a yoke for railway draft riggings, said yoke comprising upper and lower connected arms, the upper arm of said yoke being provided at its forward end with a transverse shoulder and a depending side wall, the lower arm being provided with a transverse shoulder and an upwardly extending side wall arranged opposite to the first named side wall, each of said side walls being provided with a rearward extension at its end farthest removed from the yoke arm with which it is integrally formed, said extensions being adapted to overlap the front follower of a shock absorbing mechanism assembled within the yoke. 110 115 120

5. In a device of the character described, the combination with a draw bar provided with upper and lower transversely extending shoulders, of a yoke having upper and lower arms adapted to have the distance therebetween varied, each of said arms having a 125 130

transverse shoulder at its forward end adapted to engage one of the shoulders of the draw bar when the arms of the yoke are in their normal, operative, spaced relation, 5 said shoulders of the yoke arms being adapted to be slipped over the butt of the draw bar while the yoke arms are in abnormal relation with respect to each other, and a front follower insertible laterally between the 10 arms of the yoke when the latter is assem-

bled with the draw bar, said follower engaging portions of the yoke arms at the rear of the draw bar when all of the parts are assembled and arranged to prevent relative movement between the arms of the yoke from 15 normal to abnormal positions.

In witness that I claim the foregoing I have hereunto subscribed my name this 11th day of April, 1918.

JOHN F. O'CONNOR.
